G. E. IRONS

TUNNEL KILN OIL BURNER

Filed March 27, 1920

UNITED STATES PATENT OFFICE.

GERALD ELLIS IRONS, OF CORAOPOLIS, PENNSYLVANIA, ASSIGNOR TO AMERICAN DRESSLER TUNNEL KILNS, INC., OF NEW YORK, N. Y., A CORPORATION OF NEW YORK.

TUNNEL-KILN OIL BURNER.

Application filed March 27, 1920. Serial No. 369,416.

To all whom it may concern:

Be it known that I, GERALD ELLIS IRONS, citizen of the United States, and resident of Coraopolis, in the county of Allegheny and

5 State of Pennsylvania, have invented certain new and useful Improvements in Tunnel-Kiln Oil Burners, of which the following is a specification.

The object of my present invention is to 10 provide an improved oil burner, especially adapted to extend through the wall of a furnace chamber and deliver a flame jet in a direction parallel to the wall.

The various features of novelty which 15 characterize my invention are pointed out with particularity in the claims annexed to and forming a part of this specification. For a better understanding of the invention, however, and the advantages possessed by 20 it, reference should be had to the accompanying drawings and descriptive matter in which I have illustrated and described a preferred embodiment of my invention.

Of the drawings:

25 Fig. 1 is a diagrammatic plan of a tunnel kiln fired by my improved burners;

Fig. 2 is a horizontal section of one of the burners; and

Fig. 3 is a section on the line 3—3 of Fig. 2.

30 In the drawings I have illustrated the use of my invention in connection with the well known Dressler kiln. The kiln shown diagrammatically, by way of example, comprises a kiln chamber A having combustion chambers B at opposite sides of the goods pathway through the kiln. Air is supplied to each combustion chamber B at one end from tubes or pipes C. These pipes are located in the cooling zone of the kiln, and 40 air at atmospheric temperatures entering the ends of the tubes C, remote from the combustion chambers, is heated in its passage to the combustion chambers through the tubes C. Oil is supplied to each combustion chamber B by one or more oil burners D extending through the side wall of the kiln and the outer wall of the combustion chamber at or near the end of the latter to which the tubes C are connected. The opposite end of each 45 combustion chamber is connected to tubular extensions E which run to the exit end of the

5 kiln and are connected to a stack EA, or other draft creating device for withdrawing products of combustion. Except for the special construction of the burners D, the 55 kiln illustrated comprises nothing now novel.

Each burner D, in the form shown, comprises an outer tubular shell of fire clay or like refractory material which projects through openings formed for the purpose 60 in the side wall of the kiln and combustion chamber. The inner end of this shell is closed but a circular opening D' is formed in the side of the shell toward the outlet end of the combustion chamber. Passing 65 through the fire clay shell D of each burner is an oil supply pipe F, which preferably is axially disposed in the body of the fire clay shell, and has its inner end bent at right angles to the body of the pipe, and tapered 70 to a restricted discharge outlet F', which is centrally disposed with respect to the opening D' and faces in the same direction as the latter. Surrounding the pipe F is a tubular member G, shown as having its inner 75 end formed by an elbow G' and a cap member G², and with an opening into which the discharge end of the pipe F extends, thus forming a restricted annular discharge port G³ opening into the combustion chamber 80 from the steam space G⁴ between the pipe F and the member G. Steam is supplied to the steam jacket space G⁴ by the external steam supply pipe G⁵. Oil under pressure is supplied to the burner pipes F by supply 85 pipes F². Preferably provisions are made for regulating the amount of air passing into the combustion chamber through the fire clay shell of each burner. The means shown for this purpose comprises an angularly adjustable slotted damper H journalled on the sleeve G and a stationary slotted diaphragm member I also mounted on the sleeve G. The area of the annular discharge orifice for the steam may be adjusted by screwing the cap G² up or down on the end of the elbow G'.

90 In the operation of such a kiln, as is shown in the drawings, goods are quite frequently heated to temperatures above 2500 100 F. This means substantially higher temperatures, of course, in the combustion cham-

- bers adjacent the burners. Much trouble has been experienced in attempts heretofore made to use oil as the fuel in such combustion chambers, because of carbon deposits 5 from the "cracking" of the vaporized oil, and the difficulty of providing an effective burner construction which will not be quickly destroyed or rendered inoperative by the severe conditions to which it is subjected.
- 10 With the simple and effective construction disclosed herein the metallic portions of the burner and the fire clay shell D are protected from injurious overheating by the air flow through the shell D. Objectionable 15 carbon deposits on the inner wall of the combustion chamber itself are substantially eliminated by the discharge of the burning oil axially into the combustion chambers. The deposit of carbon on the tip of the 20 burner pipe F and cap G² is prevented under normal operating conditions by the cooling effect of the steam. Furthermore the steam tends to prevent and destroy such carbon deposits both by mechanical action and by its 25 oxidizing effect. The last mentioned effect may be augmented by superheating the steam. By adjusting the damper H to regulate the flow of air through the fire clay shell of the burner, a large and determined degree 30 of superheat may be given the steam. The superheating of the steam to a substantial degree is an advantage also, in that it reduces the weight of steam required. A large degree of superheat may be obtained 35 without sacrificing the beneficial cooling effect of the air on the metallic burner parts and the fire clay shell. I contemplate the formation of the pipe F, sleeve G, elbow G', and cup G² out of an alloy having a high melting 40 point and a high resistance to oxidation such as that known commercially as "nickchrome" though steel may be employed. The metallic burner parts may be readily withdrawn for inspection and repairs when 45 necessary, and it is not difficult to replace the fire clay shell when this becomes necessary.
- It will be understood, of course, that changes may be made in the form of the apparatus disclosed without departing from the spirit of my invention as set forth in the 50 appended claims.
- Having now described my invention, what I claim as new and desire to secure by Letters Patent, is:
1. The combination with a combustion chamber having an air inlet at one end and an outlet for products of combustion at the other, of an oil burner projecting into said 55 chamber through the side wall of the latter and comprising a non-metallic refractory shell closed at its inner end except for an opening facing said outlet, and open at its outer end to receive air, an oil supply pipe in said casing having its end bent and shaped 60 to discharge a jet axially into said chamber through said opening, and a steam jacket about said oil pipe with an annular orifice surrounding the discharge end of the oil pipe. 70
2. The combination with a combustion chamber having an air inlet at one end and an outlet for products of combustion at the other, of an oil burner projecting into said chamber through the side wall of the latter 75 and comprising a non-metallic refractory shell closed at its inner end except for an opening facing said outlet, and open at its outer end to receive air, an oil supply pipe in said casing having its end bent and shaped 80 to discharge a jet axially into said chamber through said opening, a steam jacket about said oil pipe with an annular orifice surrounding the discharge end of the oil pipe, and means regulating the flow of air into 85 said chamber through said shell. 90
3. The combination with a combustion chamber having an air inlet at one end and an outlet for products of combustion at the other, of an oil burner comprising a non-metallic refractory shell projecting into said chamber through the side wall of the latter and having its end within the chamber closed except for an opening facing said outlet and receiving air at its outer end, an oil supply pipe extending into said combustion chamber within said shell and having its inserted 95 end bent and shaped to discharge a jet axially into said chamber through said opening in said shell and a fluid jacket for the 100 inserted end of said supply pipe. 105
4. An oil burner adapted to be inserted in a combustion chamber supplied with air to support combustion, said burner comprising an oil supply passage having its inner end portion bent at right angles to the body of the passage and terminating in a discharge orifice, a steam jacket surrounding said oil supply passage with a discharge orifice surrounding the first mentioned orifice, and a 110 non-metallic refractory shell enclosing the steam jacket and forming an air jacket around the latter open at its outer end to receive air, said shell being closed at its inner end except for a lateral orifice substantially coaxial with the first mentioned orifices. 115
5. An oil burner adapted to be inserted in a combustion chamber supplied with air to support combustion, said burner comprising an oil supply passage having its inner end portion bent at right angles to the body of the passage and terminating in a discharge orifice, a steam jacket surrounding said oil supply passage with a discharge orifice surrounding the first mentioned orifice, and a non-metallic refractory shell enclosing the steam jacket and forming an air jacket around the latter, said shell being closed at its inner end except for a lateral orifice sub- 125

stantially coaxial with the first mentioned orifices, and having regulable air inlets at its outer end.

6. An oil burner comprising an oil supply pipe with a restricted discharge orifice at its combustion end, a steam jacket surrounding said pipe with an annular discharge orifice surrounding the first mentioned orifice, and a non-metallic refractory shell surrounding the steam jacket and forming an air jacket 10 for the latter, said shell having an air inlet at its outer end and having an opening at its inner end through which the discharges from said orifices may pass.

Signed at Detroit, in the county of Wayne and State of Michigan, this 24th day of March, A. D. 1920.

GERALD ELLIS IRONS.
